Charles H. Schopbach and Elvin John Olds,
Aurora, Ill., assignors to International Corset
Company, Aurora, Ill., a corporation of Illinois

Application January 15, 1940, Serial No. 89,471

Term of patent 14 years

To all whom it may concern:

Be it known that we, Charles H. Schopbach and Elvin John Olds, citizens of the United States, residing at Aurora, in the county of Kane and State of Illinois, have invented a new, original, and ornamental Design for a Corset, of which the following is a specification, reference being had to the accompanying drawing, forming part thereof.

In the drawing:

Fig. 1 is a front elevational view of a corset showing our new design.

Fig. 2 is a rear elevational view of the same.

We claim:

The ornamental design for a corset, as shown.

CHARLES H. SCHOPBACH.
ELVIN JOHN OLDS.
